UNITED STATES PATENT OFFICE.

FREDERICK J. SMITH, OF HAVERHILL, MASSACHUSETTS, ASSIGNOR TO ROSA A. SMITH,
OF HAVERHILL, MASSACHUSETTS.

SHOE.

1,066,857.

Specification of Letters Patent.

Patented July 8, 1913.

Application filed February 5, 1913. Serial No. 746,308.

To all whom it may concern:

Be it known that I, FREDERICK J. SMITH, a citizen of the United States, residing at Haverhill, in the county of Essex and State 5 of Massachusetts, have invented an Improvement in Shoes, of which the following is a specification.

This invention relates to certain improvements in turned shoes and particularly in 10 turned shoes which will have the appearance of a welted shoe, but which may be made after the manner of the turned process.

Prior to my invention shoes of this general character have been manufactured by 15 sewing a welt to the inner surface of an outer sole and sewing the upper to the outer side of the inner edge portion of the welt. So far as I am aware, these shoes have not been made to more than a very limited extent, 20 particularly when machine sewed, for the reason that the welt is employed to act as a channel for the channel-guide of the sewing machine, with the result that the guide and the needle are likely to catch in 25 the stitches which attach the welt to the sole and cause serious difficulty.

The object of my invention is to provide a shoe of the above described character which will not only have the appearance of 30 a welted shoe, but will enable, as a practical matter, the manufacture of turned shoes without cutting the deep channel which is usually cut in the sole, so that the extent which the sole may be worn without wear- 35 ing through the channel may be increased, and the benefit of the full thickness of the sole may be secured. I accomplish this object by the means shown in the accompanying drawing, in which,

40 Figure 1 is a central longitudinal section of the fore-part of a shoe made according to my invention. Fig. 2 is a plan view of the outer sole as prepared for the application of the welt. Fig. 3 is a detail sectional view of the edge portion thereof. Fig. 4 is a similar view showing the sole prepared for lasting. Fig. 5 is a similar view showing the parts attached in the position before turning.

45 50 In carrying out the process of manufac-

ture which I employ, I provide an outer sole *a* and turn back a lip *a'* from the edge thereof, in an ordinary sole-channeling machine, by a horizontal knife, which simply cuts a slit in from the edge, so that the lip 55 may be turned back, as indicated in Fig. 3. This lip may be very light, and is so when a very thin sole is employed. A welt *b* is then secured to the surface *a²*, which is exposed by turning back the lip *a'*, by a 60 series of stitches *c*, which extend through the sole in the usual manner of connecting a welt to an outer sole in a welted shoe, the edge of the welt being held flush with the 65 edge of the sole.

The inner edge portion of the welt *b* is laid onto the inner surface of the lip *a'*, so that their edges are approximately even. The upper is then lasted onto the upper 70 surface of the welt, as in an ordinary turned shoe, and the upper, welt and lip are connected by a series of stitches *e*, in the ordinary manner of sewing a turned shoe, as indicated in Fig. 5. The shoe is then turned 75 in the ordinary manner, and an inner sole *f* 75 may be thereafter inserted. With this arrangement the wearing substance of the sole is practically left intact, the removal of the edge portion which constitutes the lip, reducing the sole in thickness only slightly 80 and at a point which will not affect the wearing qualities of the sole.

The groove which is formed by turning back the lip provides a smoother channel 85 for the channel-guide of the sewing machine.

By this method the cost of manufacture over that of an ordinary turned shoe is but slightly increased, while the shoe is as durable as an ordinary turned shoe having a considerably thicker sole.

90 I claim:-

A turned shoe comprising a sole having a lip turned back from the edge thereof over the inner surface of the sole and forming a channel between said surface and the lip, 95 a welt strip disposed on the opposite side of the lip from said channel and on the portion of the surface of the sole from which the lip was turned, and having the upper lying against the opposite side of 100

the welt from the lip and two series of stitches, one extending through the upper, welt and base portion of the lip to said channel and the other extending through the welt and sole adjacent the edges thereof, substantially as described.

In testimony whereof, I have signed my

name to this specification, in the presence of two subscribing witnesses.

FREDERICK J. SMITH.
